(57) **CLAIM**

The ornamental design for a bracket assembly for load restraining vehicular barrier device, as shown and described.

DESCRIPTION

FIG. 1 is a front perspective view of a bracket assembly for a load restraining vehicular barrier device showing my new design in a pre-assembled condition;

FIG. 2 is a rear perspective view thereof, of a bracket assembly for a load restraining vehicular barrier device;

FIG. 3 is a top plan view of FIG. 1, which is the mirror image of the bottom plan view;

FIG. 4 is a front elevational view of the bracket assembly for a load restraining vehicular barrier device in an assembled condition;

FIG. 5 is a rear elevational view thereof, of the bracket assembly for a load restraining vehicular barrier device;

FIG. 6 is a left end elevational view of FIG. 4; and,

FIG. 7 is a right end elevational view of FIG. 4.
